UNITED STATES PATENT OFFICE

135,843

DESIGN FOR A SPOON OR OTHER ARTICLE OF FLATWARE

James Russell Price, Cranston, R. I., assignor to
Gorham Manufacturing Company, Providence,
R. I., a corporation of Rhode Island

Application April 18, 1942, Serial No. 106,619

Term of patent 3½ years

To all whom it may concern:

Be it known that I, James Russell Price, a citizen of the United States of America, residing at 2325 Cranston Street, Cranston, Rhode Island, have invented a new, original, and ornamental Design for a Spoon or Other Article of Flatware, of which the following is a specification, reference being had to the accompanying drawing forming part thereof.

Figure 1 is a front elevation of a spoon showing my new design;

Figure 2 is a side elevation of the same spoon; while

Figures 3, 4 and 5 are cross-sections of the spoon of Figure 1 as taken on lines 3—3, 4—4 and 5—5, respectively.

I claim:

The ornamental design for a spoon or other article of flatware, substantially as shown.

JAMES RUSSELL PRICE.
